UNITED STATES PATENT OFFICE

2,590,878

SONO-OPTICAL RECORDER FOR ANTISUB-
MARINE ATTACK TRAININGWaldo K. Lyon and Robert M. Sherwood,
San Diego, Calif.

Application March 14, 1947, Serial No. 734,842

1 Claim. (Cl. 35—10.4)

(Granted under the act of March 3, 1883, as
amended April 30, 1928; 370 O. G. 757)

1

This invention relates to instruments for position indicating and more particularly to sono-optical means for locating, relative to a submerged submarine, the explosion point of an underwater flash bomb.

Indicators are known which determine the position of underwater objects in two dimensions by sound means alone. However, it is extremely desirable in many applications to indicate position in three dimensions. Examples of this are:

(1) To aid in schooling of anti-submarine attack teams by scoring the effectiveness of practice attacks;

(2) To provide a basis for experimental evaluation under controlled conditions of new ordnance, sound equipment, and methods of attack.

The object of this invention is to provide position indicating equipment which is simple, rugged, compact and which will locate objects in three dimensions.

Another object is to provide an indicator working on optical principles which will be efficient at the greatest possible ranges in sea water.

The invention also resides in certain novel features of component structure and arrangement which facilitate the carrying out of the foregoing objects and which contribute most to the simplicity of the equipment and to the reliability of operation as well as to the ease and expeditious manner of taking measurements.

In carrying out the present invention, a special constructed projectile, generating sound and light simultaneously is set and launched to explode at a position simulating the center of a normally used depth charge pattern. The equipment of our invention mounted on the target submarine will provide coordinates locating the explosion point (E. P.). Knowledge of the pattern simulated by the single projectile makes it possible to estimate whether the attack would have been lethal to the submarine. In experimental evaluation it is merely necessary to use the tested apparatus in a series of attacks, while keeping equivalent personnel and submarine tactics. The value of the apparatus will be measured by the percentage of effective hits.

The present equipment is operated from the submarine. Five hydrophones and a photoelectric cell are mounted on the deck structure in one embodiment of the invention. An amplifier-recorder is located within the submarine. The projectile is an acoustic flash bomb which emits an intense light flash and an explosive sound impulse at the same instant. This bomb may be used either as a stern dropped depth charge or an ahead thrown projectile.

2

The invention measures the time required for the transmission of sound from the explosion point to the known hydrophone points on the submarine. Since the velocity of sound in water

5 is known, the recorded times may be read as distances and the E. P. located by a triangulation method. The light flash emitted by the explosion of the acoustic flash bomb travels through the water at a velocity of 740,000,000 feet per second. Thus, it may be regarded as reaching the submarine instantaneously, affecting the photoelectric cell and its associated electrical circuit to make a mark on the recorder. The sound impulse generated at the same instant as 10 the light flash likewise travels outward but at a much slower speed of about 4800 feet per second. Accordingly, a very short but appreciable time elapses after the first or photoelectric cell mark is made on the recorder before the first of the 15 hydrophones receives a sound impulse. Electric circuits connected to this hydrophone cause another mark to be made on the recorder.

The velocity of sound in water is known and accordingly the difference in time that the two 20 marks represent may be computed to yield the distance of the E. P. from the hydrophone. In a similar manner records are made as the sound impulse reaches the other hydrophones with corresponding determination of distances. Each 25 of these distances fixes a sphere on the surface of which the explosion may have occurred.

Taking the three shortest of these distances as the most reliable, the intersection of the three 30 spheres centered at the hydrophones and having radii corresponding to the distances measured by said hydrophone is the location of the E. P. The conversion of these measured distances to location coordinates is done by use of a generalized model.

35 40 Other objects and advantages of the invention will become apparent from the following detailed description taken in connection with the accompanying drawings in which:

Figure 1 is a perspective view of a submarine 45 showing the location of the hydrophones and photocell.

Figure 2 is a block diagram of the recording equipment.

Figure 3 is a perspective view of the plotting 50 board.

Figure 4 is a bottom view of the plotting board.

Figure 5 is a view of a record taken with the 55 equipment.

Figure 6 is an elevation cross section of the projectile.

While the invention is susceptible of various

modifications and alternative arrangements, we have shown in the drawings and will herein describe in detail the preferred embodiment. It is to be understood, however, that we do not intend to limit the invention by such disclosure for we aim to cover all modifications and alternative arrangements falling within the spirit and scope of the invention as defined in the appended claim.

The relation of an explosion point to the hydrophones and photoelectric cell on a submerged submarine is shown in Figure 1. On deck 10a of submarine 10, hydrophones 11 and 12 are located near the bow and stern respectively on the center line. Hydrophone 13 is on the port deck opposite the conning tower 10b as far from the center line as possible. Hydrophone 14 is symmetrical with 13 but on the starboard side. A fifth hydrophone 15 is located on the center line of conning tower 10b in a vertical plane with 13 and 14. Photoelectric cell 16 is mounted on top of the conning tower.

Hydrophones 13, 14 and 15 are in a triangular relation in a vertical athwartship cross section. The photocell is mounted as high and clear of obstructions as possible giving maximum visibility. The photocell has its maximum output for a given incident illumination change at about the same wave length as the peak of the light transmission curve of sea water. This affords maximum distance of light reception.

In the use of the present location system, it is important that the vertical displacement of the explosion point from the deck of the submarine be determined as well as the horizontal displacement, because the ranges to be measured are usually less than three hundred feet. An error in depth may therefore be appreciable even though it is only a few feet, and the horizontal location is also determined in part by the vertical component of the displacement. The hydrophone 15 is therefore mounted on the top of the conning tower to provide a vertical base line for triangulation in a vertical direction.

The hydrophones 13 and 14 are displaced from each other on a lateral axis of the submarine to insure that the explosion point can be accurately located as occurring on the starboard or port side of the vessel as the case may be. Without the lateral base line thus established, ambiguities as to side would be impossible of resolution.

Lines D-11, D-13, D-15 indicate the distances from hydrophones 11, 13 and 15 respectively to the explosion point. Line H indicates the height of the explosion point above the deck of the submarine while line R indicates the horizontal range of the explosion point position. θ shows the azimuth.

Referring now to Fig. 2 of the drawings, the hydrophones 11, 12, 13, 14, and 15 each contain a movable contact shiftable in response to sound energy and a fixed contact in contact with the movable contact in the absence of sound so as to constitute a normally closed circuit. Hydrophones of the type described in Patent No. 1,402,420 to Heap issued January 3, 1922, may be employed, although it will be apparent to those skilled in the art that many other types of construction may be used.

As is well known, a submarine moving underwater creates considerable noise, and the sound waves created by an underwater explosion are transmitted at high intensities for considerable distances, so that the hydrophones attached to a submarine in the present invention should be relatively insensitive to require wave energy of

considerably greater intensity than that created by the submarine itself in order to open the normally closed circuit therethrough.

The photoelectric cell 16 and the hydrophones 11, 12, 13, 14, and 15 are preferably mounted on shock insulating devices to prevent injury thereto by the sound waves created by an explosion immediately adjacent one of the several units. The photoelectric cell 16 is of conventional type, such as the well-known selenium cell, and is connected with a preamplifier 17 also of conventional design, the output of the preamplifier being impressed on an amplifier 16a similar to that employed in the hydrophone circuits hereinafter described.

Each hydrophone 11, 12, 13, 14, 15 is connected with an individualized amplifier 11a, 12a, 13a, 14a, 15a respectively, each of the amplifiers comprising a trigger circuit producing a pulse of predetermined duration when the contacts of the associated hydrophone are opened by the impingement thereon of sound energy created by an explosion. A trigger circuit suitable for use in the present system is described in Patent No. 2,301,220 to Lowe, issued November 10, 1942, which circuit employs a gas tube extinguished by a capacitive discharge after ionization by the hydrophone connected therewith.

The amplifiers 11a, 12a, 13a, 14a, 15a, and 16a are each connected to an individualized stylus on the recorder 19 which consists of a metallic disc driven by a constant speed motor 20 adapted to carry a removable disc 19 of electrolytic paper which changes color upon the passage of electric current therethrough. The stylus 11b, 12b, 13b, 14b, 15b and 16b are spaced along a radius of the disc in a substantially straight line, so that a pulse from one of the several amplifiers will produce a mark on the electrolytic disc 19 at a radial distance from the center of the disc indicative of the particular amplifier.

A plotting model 21 is shown in Figures 3 and 4. A maneuvering board 22 covers the base of the model on which the positions of the deck hydrophones are simulated by location holes 11c through 15c respectively. 15c is placed in a block fitted to the base, the height of the block corresponding to the height of hydrophone 15 above the deck. Binding posts 23 are attached to the bottom of the base near the holes. Five flexible members, such as cords or wires, 11d through 15d are fastened together at one end to a connector 24. The free ends go through the hydrophone holes and binding posts. Scales 25 are attached to the bottom of the base in such a manner that the distance each wire is extended may be measured. The movable stand 26 is a stick graduated vertically in feet above the deck, or baseboard plane.

60 A record disc 19 is shown in Figure 5. Lines 29 indicate distances. The outer circle 30 is for the mark from the photoelectric cell 16. Circles 31 through 35 are for hydrophones 11 through 15 respectively. Mark 36 indicates actuation of the photoelectric cell. Marks 37, 38 and 39 indicate actuation of three of the hydrophones and due to the rotation of the disc, their displacement from mark 36 is proportional to the distances of the hydrophones from the explosion point.

65 A suitable projectile in the form of an acoustic flash bomb is shown in Figure 6. The main body of the projectile 40 carries a transparent cylinder 41 held by cap 42 which is secured by threaded tube 43 to the main body. A striker 44 is held in 70 inoperative position by aluminum wire 45. An

explosive cap 46 is located beneath striker 44; at the other end of the cap is a fuse 47. Black powder 48 is located adjacent to the fuse. Openings 49 in tube 43 lead to flash powder 50.

For operation, the motor which rotates the recording disc is started and the amplifiers, hydrophones and photocell are energized. The projectile 40 is dropped or thrown into the sea, the shock of contact with the water shearing pin 45 which permits striker 44 to detonate cap 46, in turn lighting fuse 47. A predetermined time later the fuse burns to black powder 48 exploding it, and setting off the sound impulse. Openings 49 in tube 43 permit the black powder to ignite the flash powder 50 which sets off light impulses through transparent walls 41.

Assuming the explosion is in the position relative to the submarine shown in Figure 1, the light impulses acting instantaneously will actuate stylus 16b making a mark 36 on the record 19. When the sound impulses strike hydrophone 11, stylus 11b will make mark 37 on disc 19. Impulses striking hydrophones 13 and 15 will make marks 38 and 39.

Disc 19 is driven at a constant speed by the motor which is governor controlled. The time of revolution is adjusted to bear a suitable relation to the time required for sound to travel in sea water in order to facilitate calibration. For example, the time of one revolution could be adjusted to equal the time required for sound to travel 300 feet in sea water, that is 300/4800 which equals .0625 second. Accordingly, from the angle which the disc has moved through before a record takes place, the distance from the explosion to the hydrophone making the record may be determined. In the example shown, the mark 37 indicates 192 feet as the distance from the explosion to hydrophone 11, mark 38 indicates 205 feet to hydrophone 13, and mark 39 represents 212 feet to hydrophone 15. Distance lines 29 are marked off from 36 as a zero. If desired, a transparent scale having similar lines may be placed over the record with the zero line on mark 36 to determine the distances.

In the use of the plotting model each wire is clamped so that its length from the common point to the hydrophone opening is the distance given by the record. In the instance shown, wires 11d, 13d and 15d are set at lengths corresponding to 192, 205 and 212, the other two being loose. After setting, the common junction point is held in hand and moved until all three wires are taut. The junction point then indicates the position of the explosion point and its coordinates may be read by use of the stand 26 and the maneuvering board. In the example shown, the relative bearing 0 is 300°, the horizontal range R is 212' and the height H above deck of submarine is 50'.

The invention described herein may be manufactured and used by or for the Government of the United States for governmental purposes without the payment to us of any royalties thereon or therefor.

What is claimed is:

In an anti-submarine training device employing an underwater sound and light producing explosive adapted to be ejected by a surface craft, a pair of first sound responsive devices attached to the deck of a submarine on the longitudinal axis thereof at the front and rear thereof to establish a longitudinal base line, a pair of second sound responsive devices attached to the deck of said submarine on the lateral axis at respective sides thereof to establish a lateral base line, a third sound responsive device secured to said submarine in a position vertically displaced from the deck thereof, light responsive means secured to said submarine, individualized amplifier means connected to each of said sound responsive means and said light responsive means, a recorder comprising a disc driven at a predetermined speed, and individualized stylus contacting said disc each responsive to a respective one of said individualized amplifier means to produce an indication on said disc in response to explosion of the sound and light producing explosive in the vicinity of said submarine whereby causing a first indication on said disc responsive to light and a plurality of second indications responsive to sound angularly displaced from said first indication in proportion to the distance of said explosion from respective ones of sound responsive devices thereby to permit location of said explosion in space relative to said submarine.

WALDO K. LYON.
ROBERT M. SHERWOOD.
